UNITED STATES PATENT OFFICE

136,316

DESIGN FOR AN ELECTRICAL CONTROL PANEL FOR EXAMINATION LIGHTS OR SIMILAR ARTICLE

David Conlan, Brooklyn, N. Y.

Application May 19, 1943, Serial No. 110,240

Term of patent 7 years

To all whom it may concern:

Be it known that I, David Conlan, a citizen of the United States, residing at Brooklyn, county of Kings and State of New York, have invented a new, original, and ornamental Design for an Electrical Control Panel for Examination Lights or Similar Article, of which the following is a specification, reference being had to the accompanying drawing, forming part thereof.

Fig. 1 is a front elevational view of the electrical control panel for examination lights or similar article, showing my new design and

Fig. 2 is a side elevation.

I claim:

The ornamental design for an electrical control panel for examination lights or similar article, substantially as shown.

DAVID CONLAN.
